UNITED STATES PATENT OFFICE.

JOHN C. HUNGERBUEHLER, OF PHILADELPHIA, PENNSYLVANIA; AMALIE HUNGERBÜHLER EXECUTRIX OF SAID JOHN C. HUNGERBUEHLER, DECEASED.

STRAINER FOR WASTE-PIPES.

SPECIFICATION forming part of Letters Patent No. 628,146, dated July 4, 1899.

Application filed August 18, 1898. Serial No. 688,858. (No model.)

To all whom it may concern:

Be it known that I, JOHN C. HUNGERBUEHLER, a citizen of the United States, residing in the city and county of Philadelphia, State 5 of Pennsylvania, have invented certain new and useful Improvements in Strainers for Waste-Pipes, of which the following is a full, clear, and exact description, reference being had to the accompanying drawings, of which—
10 Figure 1 is a sectional elevation showing my invention as in use in connection with a water-faucet of well-known type. Fig. 2 is an enlarged plan view; Fig. 3, a section on line xx , Fig. 2. Fig. 4 is an elevation of the splash-guard removed.

15 My invention relates to improvements in cesspools or drains for use in connection with hydrants and the like; and my object has been to provide such a device which shall be 20 simple and more efficient than any other with which I am familiar, my especial object being to prevent the splashing of the water which occurs in the well-known forms of cesspools now in use when the water is allowed to flow 25 from the faucet of the hydrant under the considerable pressure incident to the common water-supply systems.

30 My invention consists, broadly, in providing a drain-plate provided with a depending splash-guard, which latter is adapted to be placed in line with the faucet of a hydrant or the like.

35 The invention consists, further, in certain improved features and details of construction hereinafter pointed out and claimed.

Referring to the accompanying drawings, 1 is a faucet of a source of water-supply—such, for instance, as a hydrant.

2 is a funnel-shaped hopper or support, preferably of cast or sheet metal, whose lower end communicates with a drain-pipe 3, as seen in Figs. 1 and 3. Secured to the top of this support 2 is drain-plate 5, which is dished, as seen, and perforated by numerous holes 7, as 45 seen. The drain-plate 5 is in this instance secured to a flange 4 of the support 2 by bolts 6.

The drain-plate 5 is provided with a large central aperture 8, in this instance circular in form, which is surrounded by a depressed 50 flange 8^a, on which flange rests the peripheral

flange 9^a of a thimble-shaped splash guard or pot 9, which is of considerable depth and is preferably tapered toward the bottom, as seen. The lower end of this splash-guard is in this instance adjacent to the top of the drain-pipe 3, and its bottom is preferably of the concave form shown in the drawings, and near its top, below the drain-plate 5, it is perforated by a series of holes 10. The bottom of the splash-guard is also preferably provided with perforations 11.

The device is used in the following manner: Premising that the cesspool is so placed that the splash-guard 9 will be in line with the faucet 1, the latter is opened and the water escaping therefrom falls with considerable force into the said guard, but is prevented from splashing about by the side of the guard. The bottom of the splash-guard 9 being of concave form, as hereinbefore referred to, greatly aids in this result by causing the water on striking it to curl over and settle quietly, although the pressure be considerable. When the splash-guard has become 70 filled with water to the height of the holes 10, it flows therefrom into the drain-pipe 3. Should, however, the flow of water from the faucet be so great that the holes 10 are unable to carry it off and the splash-guard overflow, the perforations 7 in the drain-plate will 75 allow such overflow to pass down into the drain-pipe.

The object of the perforations 11 in the bottom of the splash-guard 9 is to allow the guard to drain when the supply of water from the faucet is stopped, so that no water will be allowed to remain in the guard when not in use. These perforations may, however, though at a disadvantage, be omitted.

The splash-guard 9 is preferably not secured to the plate 5, the flange 9^a thereof merely resting upon and being supported by the flange 8^a of the plate. The splash-guard is provided with a handle or bail 12 for conveniently removing the same when it is desired to clean or otherwise inspect the interior of the cesspool.

I remark that I do not limit myself to the precise construction of my invention shown in the drawings, as certain changes in detail 100

may be made by one skilled in the art to which my invention pertains without departing from the essence of the invention.

Having now particularly described the construction and method of use of my invention, I claim as new and desire to secure by Letters Patent—

1. In a cesspool for hydrants and the like, the combination of the drain-pipe, the foraminated, dished drain-plate supported above said pipe, and provided with a central aperture, the depressed flange surrounding said aperture, the removable, tapered splash-guard provided with the flange, 9^a, supported upon the first-mentioned flange, said splash-guard being provided with the perforations, 11, in the bottom thereof, substantially as and for the purpose set forth.

2. In a cesspool for hydrants and the like, the combination with the drain-pipe of a funnel-shaped hopper communicating therewith, the foraminated, dished drain-plate secured to the top of said hopper and provided with the central aperture, together with the thimble-shaped splash-guard fitted to and depend-

ing through said aperture and having the concave bottom, substantially as set forth.

3. In a cesspool for hydrants and the like, the combination with the drain-pipe of the hopper, 2, communicating therewith, the 30 dished, foraminated drain-plate secured to the top of said hopper and provided with the central aperture, the depressed flange surrounding said aperture, the thimble-shaped splash-guard provided with the peripheral 35 flange supported upon the first-mentioned flange, said splash-guard being provided with the holes, 10, adjacent to the top thereof, and the perforations, 11, in the bottom, together with the bail pivoted inside said splash-guard, all constructed arranged and adapted substantially as set forth.

In testimony whereof I have hereunto affixed my signature this 30th day of July, A. D. 1898.

JOHN C. HUNGERBUEHLER.
